CLAIM

The ornamental design for a mounting clamp, as shown and described.

DESCRIPTION

FIG. 1 is a front perspective view of a mounting clamp showing our new design;

FIG. 2 is a bottom perspective view thereof;

FIG. 3 is a top elevational view thereof;

FIG. 4 is a bottom elevational view thereof;

FIG. 5 is a front side elevational view thereof;

FIG. 6 is rear side elevational view thereof; and,

FIG. 7 is a left elevational view thereof and the right elevational view is a mirror image of the left elevational view.

The broken lines shown in FIGS. 2 and 4 and the areas within the broken lines depict portions of the mounting clamp that form no part of the claimed design.

1 Claim, 3 Drawing Sheets
